(57) **CLAIM**

The ornamental design for a rig for electrophoresis gel casting, as shown and described.

DESCRIPTION

This application is related to U.S. Non-Provisional patent application Ser. No. 15/349,106 entitled "Preparation of Electrophoresis Gels, and Related Devices, Systems, and Methods," filed Nov. 11, 2016; to U.S. Design patent application Ser. No. 29/545,620 entitled "Electrophoresis Gel Cassette," filed Nov. 13, 2015; to U.S. Design patent application Ser. No. 29/545,633 entitled "Cassette Support Base for Electrophoresis Gel Casting," filed Nov. 13, 2015, now U.S. Pat. No. D816,865; and to U.S. Design patent application Ser. No. 29/545,635 entitled "Cassette Clamp for Electrophoresis Gel Casting," filed Nov. 13, 2015, the entire contents of each of which are incorporated by reference herein.

FIG. 1 is a front perspective view of a embodiment of a rig for electrophoresis gel casting showing our new design.

FIG. 2 is a back perspective view thereof.

FIG. 3 is a front view thereof.

FIG. 4 is a back view thereof.

FIG. 5 is a right side view thereof.

FIG. 6 is a left side view thereof.

FIG. 7 is a top view thereof.

FIG. 8 is a bottom view thereof.

FIG. 9 is a front perspective view of another embodiment of a rig for electrophoresis gel casting showing our new design.

FIG. 10 is a back perspective thereof.

FIG. 11 is a front view thereof.

FIG. 12 is a back view thereof.

FIG. 13 is a right side view thereof.

FIG. 14 is a left side view thereof.

(Continued)

FIG. 15 is a top view thereof; and,
 FIG. 16 is a bottom view thereof.
 The broken lines represent portions of the rig for electro-
 phoresis gel casting that form no part of the claimed design.
 The broken lines form no part of the claimed design.
